Herman E. Crawford, Kernersville, N. C.

Application April 26, 1954, Serial No. 30,165

Term of patent 14 years

(Cl. D47—7)

To all whom it may concern:

Be it known that I, Herman E. Crawford, a citizen of the United States of America, residing at Kernersville, in the county of Forsyth, State of North Carolina, have invented a new, original, and ornamental Design for a Sock, of which the following is a specification, reference being had to the accompanying drawing, forming a part thereof.

I claim:

The ornamental design for a sock, substantially as shown and described.
